US00D965440S

(12) **United States Design Patent** (10) Patent No.: **US D965,440 S**
Lee et al. (45) Date of Patent: ** *Oct. 4, 2022

(54) **PACKAGE**(71) Applicant: **The Procter & Gamble Company**,
Cincinnati, OH (US)(72) Inventors: **Yun Qin Lee**, Singapore (SG);
Toshiyuki Okada, Singapore (SG)(73) Assignee: **The Procter and Gamble Company**,
Cincinnati, OH (US)

(*) Notice: This patent is subject to a terminal disclaimer.

(**) Term: **15 Years**(21) Appl. No.: **29/761,112**(22) Filed: **Dec. 7, 2020**(30) **Foreign Application Priority Data**

Jun. 29, 2020 (CN) 202030339197.8

(51) LOC (13) Cl. **09-01**
